UNITED STATES PATENT OFFICE.

FRED SCHULZ, OF FRUITVALE, CALIFORNIA.

HYDROCARBON BURNER.

1,415,123.

Specification of Letters Patent. Patented May 9, 1922.

Application filed July 20, 1921. Serial No. 486,285.

To all whom it may concern:

Be it known that I, FRED SCHULZ, a citizen of the United States, residing at Fruitvale, in the county of Alameda and State of California, have invented certain new and useful Improvements in Hydrocarbon Burners, of which the following is a specification.

The present invention relates to a gaseous fuel burner, and the same has for its principal object to provide a burner construction wherein the air for mixing with the fuel admitted to the burner and the air for combustion is capable of simultaneous proportionate variation or control.

A further object is to provide a burner body divided by a Venturi plate adapted for adjustment affording a plurality of mixing chambers for the fuel and air, the area of which may be readily varied to obtain the most efficient results.

Another object is to provide an improved form of burner head enclosing the burner body, and of cylindrical or conical formation providing a maximum burner area and occupying a minimum space.

Among the other objects are to provide a construction wherein the back-firing of the gaseous mixture to a point where the same ignites from the feed pipe is precluded, and wherein an air supply for combustion is provided centrally through the burner without being open to the gaseous fuel mixture, and to provide a novel formation of valve plate or control whereby the operation thereof permits of the simultaneous variation or adjustment of the air admitted into the primary mixing chamber to intermix with the fuel and the air admitted into the secondary or combustion chamber to afford perfect combustion, insuring the proper proportion of air for the respective purposes at all times.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein:

Figure 1 is a vertical sectional view of one embodiment of my invention.

Figure 2 is a transverse sectional view taken on line 2-2 of Figure 1, viewed in the direction of the arrows.

Referring more particularly to the drawings wherein like characters of reference designate corresponding parts, 1 indicates a tubular burner body open at its upper end as at 2, and the wall forming the lower end thereof being outwardly and downwardly flared, as at 3, providing a primary mixing chamber 4 of substantially conical formation. The inner surface of the wall forming the burner body 1 at a point immediately above the chamber 4 is interiorly threaded as at 5, and receives a Venturi plate 6 formed with a Venturi opening 7. The plate 6 divides the body 1 into the lower primary mixing chamber 4, and the upper mixing chamber 8. Thus it will be apparent that the plate 6 is adapted for vertical adjustment within the body 1 to vary the area of the respective chambers 4 and 8 and to enable the adjustment of the plate within the body to such a position as to preclude the back-firing of the gaseous mixture passing through the opening 7. Adjacent its lower end, and above the threads 5, the tubular burner body 1 is provided in its wall with one or more ports 9, and is also formed on its interior below said ports with an annular supporting flange 10, and on its outer surface above said ports with a laterally extending head supporting flange 11. My improved burner head consists primarily in the tubular stem 12 provided at its lower end with the lateral channels 13, the lower surface of which rest on the flange 10 when the stem 12 is inserted downwardly into the burner body 1 through its upper open end 2 with the channels 13 in register with the ports 9 affording an air passage through the channels 13 and stem 12.

It will be observed that the stem 12 is of a diameter considerably less than the interior diameter of the body 1, and said stem 105 is of such length as to space the perforated relatively flat top wall 14 thereof a slight distance above the upper open end 2 of the body 1. The portion 14 is preferably of an annular formation, and from the edge thereof 110

depends a perforated skirt 15 adapted to rest in the suitable annular groove at the periphery of the flange 11. It will be observed that the skirt 15 and portion 14 provide a chamber 16 enclosing the upper end 2 of the body 1, and that said burner is of comparatively small diameter but of great depth affording a considerable combustion space occupying relatively little area. Extending upwardly into the primary mixing chamber 14 and discharging axially thereinto is a fuel supply nozzle 17 adapted to be supplied preferably with gaseous fuel from any suitable source, and the same affords a support or mount for the supporting plate 18 on which said burner body rests. Co-operating with the plate 18 and positioned preferably beneath the same is a valve plate 19 held in contact with the plate 18 by a nut 20 threaded on the fuel supply nozzle 17 below the flange 18' thereof. Surrounding the burner body 1 and extending to a point at least to the top of the burner head is a tubular shell 21 resting at its lower edge inside of a flange 22 extending upwardly from the plate 18, and said shell forms between the burner body 1 and its inner surface a combustion chamber 23 through which is admitted a controllable quantity of air to insure proper combustion. The air control for the primary chamber 4 and the combustion chamber 23 is afforded through the double annular series of ports 24 and 24' formed in the plate 18 respectively at the base of the chamber 4 and the chamber 23, and with this series of parts co-act similar ports 25 and 25' formed in the valve plate 19, as clearly illustrated in Figure 2. The adjustment of the plate 19 axially about the nozzle 17 causes the solid portion of the plate to vary the effective area of the ports 24 and 24', thereby simultaneously controlling the air admitted into the respective chambers 4 and 23. If desirable, a burner igniting device 26 may be provided and extend through an opening 27 in the wall of the shell 21 at a point in close proximity to the burner head, thereby enabling a pilot flame to be maintained from which the igniting of the burner is accomplished, on gas being admitted through the nozzle or jet 17.

It will be observed that a portion of the air admitted into the combustion chamber passes through ports 9, channels 13 and into the tubular stem 12 discharging centrally of the perforated top 14 of the burner head insuring ample air to accomplish efficient combustion.

Having thus described my invention, what I claim as new and desire to secure by Letters Patent of the United States is:—

1. A gaseous fuel burner including a tubular body provided with an interiorly threaded portion, a burner head carried by the

body, a fuel supply nozzle discharging into the body, a Venturi plate having a threaded periphery and disposed transversely within the body dividing its interior into the upper and lower mixing chambers, said engaging threads of the tubular body and plate affording an adjustment for said plate longitudinally within said body to vary the relative areas of said chambers without varying the length of said body, and a valve control air inlet for the lower chamber. 70

2. A gaseous fuel burner including a tubular body, a burner head carried thereby and arranged to envelope one end thereof with a portion of the burner extended over the side of the tube, a fuel supply nozzle discharging into the body, a tubular shell surrounding the burner and affording a combustion chamber, and simultaneously controllable air inlet ports at the base of said body and combustion chamber. 80

3. A gaseous fuel burner including a tubular body, a burner head carried thereby, a fuel supply nozzle discharging into the body, a tubular shell surrounding the burner and affording a combustion chamber, a plate supporting said body and shell and provided with a series of ports, one communicating with the lower end of said combustion chamber, and another with the base of said body affording separate air inlets therefor, and a ported valve plate co-operating with said supporting plate and movable thereover for simultaneously varying the area of said inlets. 90

4. A gaseous fuel burner including a tubular body provided with an aperture in its wall, a head fitted over the upper end thereof and including a tubular stem extending centrally into said body, and formed at its lower end with a lateral channel communicating with said port affording an air passage disposed centrally through said burner, said head formed with a perforated top wall and a perforated skirt extending downwardly therefrom in spaced relation to the upper end of the body, a fuel supply nozzle discharging into said body, a tubular shell surrounding the burner and affording a combustion chamber, and means for simultaneously controlling the admission of air into the lower end of said body and into said combustion chamber. 100

5. A gaseous fuel burner including a tubular body, a head fitted over the upper end thereof and formed with a perforated top wall and a perforated skirt extending downwardly therefrom in spaced relation to the upper end of the body and enclosing the same providing a chamber into which said body discharges, a fuel supply nozzle discharging into the lower end of the body, a Venturi plate disposed transversely within said body dividing the same into upper and lower mixing chambers, and means for con- 110 115 120 125 130

trolling the admittance of air into the lower mixing chamber.

6. A gaseous fuel burner including a tubular body formed with a flared lower end 5 affording a contracted throat and provided adjacent to its upper end with an annular flange, a head enclosing the upper end of said body and provided with a perforated top wall and a perforated skirt extending 10 downwardly therefrom and resting on said flange affording a chamber surrounding the upper end of the head and into which the same discharges, a Venturi plate disposed

transversely of the lower end of said throat dividing said body into upper and lower 15 mixing chambers, a fuel supply nozzle discharging axially into said burner mixing chamber, a tubular shell surrounding said body and extending above said head, and a valve for simultaneously varying the air 20 volume admitted into said mixing chamber and into the combustion space afforded between the body and shell.

In testimony whereof I have signed my name to this specification.

FRED SCHULZ.
